UNITED STATES PATENT OFFICE

170,841

TABLE LAMP

Jule Vigon, Los Angeles, Calif.

Application May 21, 1953, Serial No. 25,132

Term of patent 14 years

(Cl. D48—20)

To all whom it may concern:

Be it known that I, Jule Vigon, have invented a new, original, and ornamental Design for a Table Lamp, of which the following is a specification, reference being had to the accompanying drawing, forming a part hereof.

Fig. 1 is a front elevational view of a table lamp embodying my new design.

Fig. 2 is a side elevational view of the same.

Fig. 3 is a top plan view of the same.

I claim:

The ornamental design for a table lamp, substantially as shown.

JULE VIGON.
